UNITED STATES PATENT OFFICE.

GUSTAVE F. SCHMIDT, OF CHICAGO, ILLINOIS.

GAS HEATER.

Application filed December 27, 1921. Serial No. 524,941.

To all whom it may concern:

Be it known that I, GUSTAVE F. SCHMIDT, a citizen of the United States, and a resident of Chicago, in the county of Cook 5 and State of Illinois, have invented certain new and useful Improvements in Gas Heaters, of which the following is a description, reference being had to the accompanying drawings, which form a part 10 of my application.

My invention relates broadly to gas heaters or radiators and more particularly to the type employing a plurality of heat radiating elements or radiants in conjunction with a burner provided with a plurality of tips corresponding in number with the heat radiating elements or radiants, which are supported by suitable means independently of the burner.

20 My invention contemplates a construction which will be separate from and to that extent independent of the burner per se, and which is so formed that the heater proper may be placed over the burner after 25 the latter has been secured in place at the desired point and the necessary gas connections have been made; thereby providing a heater which will permit ready access to the burner without necessitating a complete dismantling of the heater proper or 30 separation of the various parts constituting the heater.

One object of my invention is to provide a heater, so far as the general body portion is concerned, consisting of two units, the one unit constituting the main body portion, while the other unit constitutes a black-wall or radiant-holding member; with the black-wall unit being readily removable and loosely held in place without employing fastening means requiring the use of any special tools or sheet metal fastenings or enclosures.

Another object of my invention is to provide a gas heater in which the two main units may be made of earthen material, as for example majolica or any suitable clay; and the outer surfaces of said units may be glazed or provided with a suitable enamel 50 or finish of any desired color in keeping with or adapted to harmonize with the furnishings and finish of the apartment or room in which the heater is to be placed; with the result that a more artistic heater 55 is provided than is possible with heaters as heretofore constructed out of metal.

A further object of my invention is to provide a heater, which, when made of earthen material as above stated, will be of special formations adapted to take care of any unequal expansion and contraction that may result while the heater is in use; at the same time providing a construction wherein a more perfect combustion may be obtained by reason of air passages at predetermined points to permit a proper circulation of air and therefore a more effective radiation induced.

The objects and advantages of my invention will all be more fully comprehended 70 from the detailed description of the accompanying drawings, wherein:

Figure 1 is a front elevation of one form of my improved heater.

Figure 2 is a sectional view taken on the 75 off-set line 2—2 of Figure 1 looking in the direction of the arrows.

Figure 3 is a vertical sectional view taken on the line 3—3 of Figure 1, looking in the direction of the arrows. 80

Figure 4 is a front perspective view of the back-wall unit.

Figure 5 is a perspective view of a portion or one end of the radiant rest.

Figure 6 is a detail plan of a burner tip. 85

Figure 7 is a sectional view taken on the line 7—7 of Figure 6.

Figure 8 is a perspective view of one end of the body unit having a configuration substantially similar to that shown in Figures 1 and 2 and disclosing a slight modification. 90

Figure 9 is a perspective view of a modified form of back-wall unit adapted for use in connection with the body unit illustrated in Figure 8. 95

Figure 10 is a detail vertical sectional view of the back-wall unit shown in Figure 9 with a portion of the body unit illustrated in Figure 8, showing the back-wall 100 unit in place.

Figure 11 is a perspective view of another form of my improved heater, with a portion of the radiants removed.

Figure 12 is a modified form of back-wall 105 unit adapted for use more particularly with the type of body unit disclosed in Figures 1 and 2 and provided with a removable top.

While the features of my invention in many respects may be employed in gas heaters, of the radiant type, made of metal, 110 they are especially adapted to gas heaters

composed of earthen material, such as majolica or other suitable clay, which may be provided with a proper glaze or enamel whereby an artistic appearance may be provided in keeping with the desires of the user and in harmony with the furnishings of the room in which the heater is to be placed.

In its specific embodiment as disclosed in the first three figures of the drawings, it 10 comprises the main body portion or unit consisting of the two end columns or portions 15, 15, united at the bottom by means of the base portion or webs 16, 16, all formed integral and molded into shape with a configuration especially adapted to resist the 15 heat and to compensate for expansion and contraction. The body unit is molded out of clay, such as majolica, and therefore has the end columns or portions 15, 15 made 20 hollow from top to bottom while the connecting base or webs 16, 16 are preferably arched to provide a suitable opening therebeneath, as at 17, to permit air circulation. The base or connecting web portion 16 is 25 chambered or hollowed out to receive a suitable burner indicated at 18, which is absolutely independent of and disconnected from the heater and which, in my improved construction, is adapted to be supported by 30 suitable standards as at 19 and 20 adapted to be fastened to the floor at the point where the heater is to be located; the standard or support 20 being shown of less height because of its attachment to the mixing chamber 35 portion 21 of the burner; namely the portion provided with the usual hand operated valve whereby the flow of gas into the burner is controlled and which is also provided with the air-admitting slide, usual 40 in the Bunsen type of gas burner generally employed. The burner is provided with a plurality of tips on which is supported a metallic plate or radiant-rest 22 adapted to extend the full length of the burner and 45 therefore intermediate of the column portions 15, 15 and supported by the burner. The radiant rest 22 is preferably of the construction more clearly shown in Figure 5, provided with openings as at 23 adapted 50 to receive the burner-tips, while the upper surface, intermediate of the openings 23 are preferably provided with upwardly projecting lugs 24, see Figures 2 and 5, which 55 constitute spacing lugs for determining the position of and for maintaining the lower ends of the radiants, indicated at 25, in proper position. As the radiants may be of the usual well known construction employed in what are known as radiant gas heaters 60 and form no part of my invention, a specific description thereof need not be entered into.

The connecting web or base portion 16, intermediate of the columns or end portions 15, 15, is provided with the slot as at 26, see

Figure 3, of somewhat greater width than the width of the tips of the burner and also preferably slightly greater than the width of the radiant rest or plate 22, in order to leave a slight space intermediate of the plate 70 22 and the lower edge of a back-wall unit 27. The back-wall unit 27, in the construction illustrated, is also made of refractory material or majolica like the main body unit 75 in order that the rear side and top surface, namely the portions which are exposed, may also be glazed or enameled. The back-wall 27 is made separate from the body unit and is intended to rest on the upper surface of the connecting web or base portion 16 and 80 preferably separated therefrom at the bottom by a suitable asbestos gasket or strip 28, see Figure 3. The back-wall unit 27 is formed with the forwardly presented sides 85 or ends 29, 29 and with a forwardly overhanging top portion 30, formed integral when the sides and the main portion of the back as very clearly shown in Figure 4; in other words, the back-wall unit 27 may be 90 said to be recessed on its front face to receive the radiant elements 25. In order that the upper ends of the radiant elements 25 may be held against accidental displacement, I prefer to have the lower face of the 95 top portion 30, provided preferably with a plurality of sockets 31, which may either be a continuous socket or channel lengthwise of the top 30, or a series of separate sockets 100 separated by the web portions 32, which will ensure the upper ends of the radiants being maintained in slight spaced relation as disclosed in Figure 1. To ensure the back-wall unit 27 being held in place on the body unit, I show the outer surfaces of the sides or end portions 29, 29, provided with a channel 33 105 extending from the bottom to a point adjacent the top, while the inner adjacent sides of the columns or end portions 15, 15 of the main body unit are in turn provided with projections or lugs 34, 34 see Figure 2, 110 adapted to fit into the recesses or channels 33; the lugs or projections 34 being formed at any suitable point on the inner adjacent faces of the columns or end portions 15, 15. It is evident from the construction shown and described that the back-wall unit may 115 be slid into and out of place by simply lifting the back-wall unit upwardly, allowing the lugs or projections 34 to ride through the lower open end of the sockets or channels 33. This construction not only permits a ready assembly of the radiants 25, but it will also be apparent that access to the 120 burner-tips may be had without necessitating removal of the entire heater.

Where the heater is made of a suitable clay, such as majolica, the provision of a separate back-wall unit will compensate for the differences in expansion and contraction 125 of the entire heater, because the back-wall

unit will be subjected to the greatest degree of heat and if made integral with the main or body unit would be apt to result in cracking or breaking due to the unusual variance in expansion and contraction. It will be understood, of course, that the fit between the back wall unit and the main or body unit is not extremely snug, but just sufficient to maintain the back-wall unit in place by the 5 lugs or projections 34 disposed into the grooves or channels 33, thus allowing for sufficient expansion on the part of the back-wall unit in excess of any expansion resulting in the main or body unit. Furthermore, 10 in order to eliminate any possibility of the back-wall unit cracking or breaking through excessive heat, I prefer to provide the front surfaces of the forwardly projecting sides or ends 29, 29 of the back-wall unit with 15 slight cuts or slits as at 35, 35, of comparatively shallow depth, while the overhanging portion of the top 30 of the back-wall unit is also preferably provided with a similar cut or slit as at 36 see Figure 1. It 20 has been found in practice that with these cuts or slits, breakage of the enamel or glaze on the back-wall unit, due to excessive heat, will be prevented; it being understood that these cuts or slits are comparatively 25 narrow cuts and merely extend to a slight depth in the side portions 29 and the top portion 30.

The lower ends of the columns or end portions 15, 15, adjacent the bottom thereof, may be provided with small openings, preferably arched as at 37, see Figure 3, which not only permit a greater circulation of air beneath the bottom of the heater—and upward about the radiants—but one of the 30 openings 37 also provides a passage for the usual hand-valve whereby the flow of gas to the burner is controlled.

In Figures 8 to 10, I show a modification of my invention, wherein the columns or end portions 15^a of the body unit, like in the construction shown in Figure 1, is formed integral with the connecting web or base portion 16^a which is formed with a flat surface on the upper side, slotted longitudinally at 26 as in the previously described construction. The columns or end portions 15^a of the body unit are each provided with a pair of lugs or projections 38 and 39, the former being disposed at a point slightly removed 30 from the upper end of the end portions while the lug 39 is preferably arranged adjacent to the top surface of the connecting web 16^a, namely at the ends of the slot 26 see Figure 8. The remainder of the body unit may be identical in construction and configuration with that shown in Figures 1 and 2, and the general construction of the back-wall unit 27^a may be identical with that shown in Figure 4, except that the sides or ends 29^a in this instance have the longitudi-

dinal channels or grooves 33^a open toward the rear side of the back-wall unit as shown at 40, in order that the back-wall unit may be put into place from the front side of the heater by positioning the back-wall unit so 70 that the open side 40 of the channels 33^a will permit passage of the lugs 38, as shown when the back-wall unit is in the position indicated in dotted lines in Figure 10 and then sliding the back-wall unit downwardly, permitting it to be suspended from or supported by the lugs 38, as shown in full lines in Figure 10, at which time the lower end of the channels or grooves 33^a will receive the 75 lugs or projections 39 on the end portions 15^a 80 of the body unit, thereby maintaining the back-wall unit in place against accidental displacement, and if desired leave a slight space beneath the back-wall unit for insulation from the body-unit.

In Figure 11, I show a further modification of my invention, more particularly in so far as the configuration of the main body unit is concerned, wherein the side portions or ends 41, 41 are of a more or less rectangular configuration, tapering toward the tops, with their opposing inner sides shown provided with the longitudinal ribs or ridges 42 arranged lengthwise of the opposite longitudinal edges, to provide a 90 groove or slideway therebetween into which the ends of the back-wall unit 43 are adapted to extend; thus permitting the back-wall unit to be put into place or removed by simply sliding the same vertically from or to the upper end of the end portions or sides 41 of the main unit. The back-wall unit, like the back-wall units previously described, has the ends projecting somewhat 95 forwardly as is also the case with the top portion 44 thereof so as to provide a radiant receiving recess on the front face of the back-wall unit; said unit being adapted to rest on the connecting web^{*} portions 16^b of 100 the body unit, formed similar to the web portions in the previously described constructions, namely in so far as the upper face thereof is concerned, in order to provide a slot-way similar to slot 26, for the 105 reception of the burner-tips and the radiant rest or plate 22. The overhanging top portion 44 of the back-wall unit is also preferably provided with a channel into which the upper ends of the radiants 25 may extend to prevent them from becoming displaced or tipped forwardly.

The back-wall unit is also preferably provided with a slight slit or cut as at 46, like the slit 35 in the construction shown in Figure 1, to 115 compensate for expansion and contraction and thus prevent breakage or cracking of enameled or glazed surface and for a similar reason the connecting web 16^b at the rear side of the body unit, on which the back-wall unit mainly rests, may likewise 120 125 130

be provided with a cut or slit, because the back-wall unit is subjected to the greatest amount of heat, which may be somewhat transferred to the rear connecting web.

- 6 As one object of my invention is to provide a radiant gas heater made out of majolica or suitable earthen material, the various units, more particularly the body units, are made of the hollow construction 10 and in the designs presented in the drawings which are especially adapted to take care of varying degrees of expansion and contraction resulting from certain parts of the heater being in very close contact with 15 the radiants and the products of combustion which will cause such parts to expand more rapidly than is the case with the more remote portions. Unless a special construction therefore is provided, breakage of the 20 clay would be very apt to occur and blistering of the glazed or enameled surface would be encountered and for that reason I employ the expansion and contraction seams or slits shown and the more or less loose fit 25 scribed between the back-wall unit and the body unit.

In Figure 12, I illustrate a modified form of back-wall unit wherein the main portion of the unit 47 is provided with the forwardly projecting side walls or end portions 48 whose outer faces are each provided with the longitudinally disposed channel or groove 49, shown extending from top to bottom, to adapt the back-wall unit for 30 use with a body unit provided with lugs or lips like those shown at 34 in Figure 2 arranged lengthwise of the inner opposing faces of the end portions or columns, enabling the back-wall unit to be inserted into 35 place and removed by sliding the back-wall unit vertically from or to the upper ends of the end portions or columns of the body unit. In the modification shown in Figure 40 12, the top portion 50 is formed separate and apart from the main portion of the 45 back-wall unit; the lower face of the top 50 being preferably provided with a series 50 of sockets 31, like those in the unit shown in Figure 4, into which the upper ends of 55 the radiants 25 extend when the latter have been put into place on the supporting plate 22 mounted on the burner-tips. The lower surface of the top portion 50, adjacent the ends thereof, is also shown provided with 60 the depending lugs 51, 51 formed to register with and to depend into the upper ends of the grooves or channels 49 in the outer faces of the sides or end portions 48 of the back-wall unit. With this construction, the back-wall unit 47 is first put into place by sliding 65 the same vertically downward onto the connecting web or base of the body unit with the lugs on the adjacent inner surfaces of the columns or end portions arranged 85 within the grooves or channels 49; the top

portion 50 is then put into place by having the lugs 51 extend into the grooves or channels 49. It is clearly evident that the back-wall unit will be removably held in place as is also the case with the top portion 50; thus permitting the easy assembly or disassembly of the respective parts of the heater; while the separate and non-rigidly connected units of the heater will permit of unequal expansion and contraction of the 75 respective units without affecting each other.

In my improved heaters, the radiant rest 22 is shown, at what constitutes its forward edge, provided with an upwardly and downwardly disposed flange 23^a which is adapted to rest on the upper surface of the main portion of the burner adjacent to the tips thereof, while the upwardly disposed portion of the flange 23^a will prevent the lower ends 85 of the radiants 25 from becoming displaced or moving forwardly out of proper register with the respective burner-tips. The back-wall units of my heater are adapted to rest entirely on the upper surface of the rear 90 connecting web or base portion of the body unit, as more clearly shown in Figure 3; while the longitudinal slot or space between the upper surfaces of the connecting webs of the main or body unit and the width of the 95 radiant rest are so correlated that a proper air space between the back-wall and the radiant rest is provided, which enhances combustion and at the same time prevents the transference of heat from the back-wall 100 unit through the metallic radiant rest to the body unit of the heater. As the radiant rest is preferably of metal, it necessarily will constitute a heat conductor and for that reason I prefer to employ an asbestos gasket 105 intermediate of the radiant rest and the burner in order that the heat from the radiant rest may not be transferred to the burner per se, as improper heating of the burner interferes with its proper operation 110 and is likely to cause a backflash or fire. With my improved construction, the metal portions of the heater, to-wit the burner and the radiant rest, are out of intimate contact 115 with the majolica or clay body of the heater either because of the air-space provided therebetween or the employment of suitable insulation, such as asbestos gaskets.

My improved heater body, as is apparent from the drawings, is absolutely independent 120 of the burner; and in practice the burner is first secured in place at the desired point on the floor, after which the heater body is placed over the burner, with the latter disposed within the hollow base portion intermediate of the sides or ends and immediately beneath the space or slot 26 arranged in the top surface of the connecting webs of the body unit. The forward recessed face 125 of the back-wall unit is shown preferably 130

formed corrugated or fluted as at 52 and slightly receding toward the top, which not only permits a slight lean or inclination on the part of the radiants to prevent accidental displacement, but also provides sufficient air space intermediate of the front face of the back-wall unit and the radiants which enhances combustion and increases radiation. In constructing the heater body and back-wall out of majolica or heat-resisting clay, I am enabled to provide a heater with an enameled or glazed surface of greater artistic appearance than is the case with heaters as heretofore employed and made of metal; at the same time providing a heater adapted to withstand the high temperatures to which it is subjected when in use.

In order to ensure a proper positioning of the radiants and to compensate for any slight inaccuracies on the bottoms thereof, I prefer to construct the radiant rests 22 with a slight rearward and downward slope, thereby preventing the possibility of the radiants having a forward inclination toward the top. Furthermore, in order to take care of slight differences that may exist between the length of the radiants and the distance from the radiant rest to the sockets in the top portion of the back-wall unit, I provide the top surface of the burner at suitable points intermediate of the tips with a pair of bosses having tapped openings adapted to receive the threaded ends of the screws or bolts 53 which pass through suitable openings at the ends of the radiant rest 22; the screws or bolts being shown provided with washers at 54 disposed beneath the radiant rest to support the same in its adjusted position. With this construction, it is apparent that by screwing the bolts or screws in proper direction, the radiant rest may either be raised or lowered as desired.

I have shown specific exemplifications of my invention which have been described in terms employed merely as terms of description and not as terms of limitation, as structural modifications are possible and may be made without, however, departing from the spirit of my invention.

What I claim is:—

1. A gas heater of the character described, comprising a body unit provided with upstanding ends or columnar sides and an integral intermediate hollow base portion, the base portion being formed with a longitudinal burner-tip receiving opening, and a back-wall unit adapted to be disposed on said intermediate base portion of the body unit, the columnar sides of the body unit and said back-wall unit being provided with interlocking surfaces for removably securing the back-wall unit in place, in combination with radiant elements arranged along the front face of said back-wall unit and above said burner-tip receiving opening.

2. A gas heater of the character described, comprising a body unit consisting of integral hollow base portions and upstanding end portions, the opposing faces of the upstanding end portions being provided with projections while the base portion intermediate of said upstanding ends is formed with a burner-tip receiving opening, and a recessed back-wall unit removably seated on the base portion intermediate of the upstanding ends of the body unit, the ends of the back-wall unit being formed to provide interlocking relation with the projections on said upstanding ends of the body unit to removably hold the back-wall unit in place, a burner disposed in the hollow base portion beneath the burner-tip receiving opening, a radiant supporting member arranged in said opening and adjustably secured to the burner, and a plurality of radiant elements arranged along the front face of said back-wall unit on said supporting member.

3. A gas heater of the character described, comprising a body unit having a hollow base portion provided with upstanding ends integral therewith, the intermediate part of said base portion being provided with an elongated slot extending from one upstanding end to the other, and a separate back-wall unit adapted to be disposed intermediate of the upstanding ends and to rest on the intermediate portion of the body unit, said back-wall unit being provided with a forwardly projecting top socketed on its lower face, the body unit and back wall unit being provided with interlocking portions for removably securing the back-wall unit in place, a radiant supporting member arranged in said elongated slot, in combination with radiant elements arranged on said supporting member along the front face of the back-wall unit with their upper ends disposed in the socket of the forwardly projecting top of the back-wall unit.

4. A gas heater composed of heat resisting clay, comprising a body unit having upstanding ends integrally connected together at their bottoms by a base portion provided with a burner-tip receiving opening in the upper face thereof intermediate of said ends, and a back-wall unit having a recessed front face and a forwardly projecting top, said forwardly projecting top being recessed on its under surface, the ends of the back-wall unit and upstanding ends of the body unit being formed to have interlocking relation for removably holding the back-wall unit in place, in combination with radiant elements arranged in said recessed front face of the back-wall unit above the burner-tip receiving opening, with the upper ends of the elements disposed in the recessed lower surface of the projecting top of the back-wall unit.

5. A gas heater composed of heat-resist-

- ing clay and comprising a body unit having upstanding ends integrally connected together at the bottom by a base portion, the base portion intermediate of said upstanding ends being provided with an elongated burner-tip receiving opening, and a back-wall unit having forwardly projecting ends and a top, said back-wall unit and body unit being formed to have sliding interlocking relation with each other and each provided with slits at predetermined points to compensate for unequal expansion and contraction.
6. A gas heater composed of heat resisting clay and comprising a body unit having integrally formed upstanding ends and a hollow base portion adapted to be disposed over a gas burner independent thereof, said base portion intermediate of the upstanding ends being slotted to receive the burner-tip, a radiant rest disposed in said opening on the burner and out of heat conducting relation with the body unit and adapted to permit air circulation thereabout,
- 10 20 25 30 35 40 45 50 55 60 65 70 75 80 85 90 95 100 105 110 115 120 125
- and a back-wall unit disposed on the base portion intermediate of the upstanding ends of the body unit and provided with a socketed overhanging top, the body unit and back-wall unit being provided with interlocking surfaces whereby the back-wall unit is removably secured in place, in combination with radiant elements arranged on said radiant rest adjacent the front face of the back-wall unit, with the upper ends disposed in the socket of the overhanging top whereby said elements are held in place.
7. A gas heater of the character described, comprising a body unit, a back-wall unit and radiant elements, the body unit being provided with upstanding ends and with a base portion formed integral with the lower part of said ends, the base portion being slotted intermediate of said upstanding ends to provide a burner-receiving opening, while the ends of the back-wall unit are adapted to form interlocking relation with the upstanding ends of the body unit to removably hold the back-wall unit in place, said back-wall unit being provided with a removable top whose lower face is socketed to receive the upper ends of the radiant elements.
8. A heater of the character described, composed of heat-resisting clay and consisting of a body unit having upstanding ends while the intermediate base portion is provided with an elongated burner-tip receiving opening, a back-wall unit formed to provide interlocking relation with the upstanding ends of the body and having an overhanging top recessed on its lower face to receive the upper ends of radiant elements, in combination with a radiant rest adapted to be disposed on the burner with-65 in the burner-tip receiving opening of the
- body unit, and means whereby said radiant rest is insulated from said body unit.
9. In a gas heater of the character described, comprising a body unit having upstanding ends formed integral with a hollow base portion having a burner-tip receiving opening in the upper face thereof intermediate of said ends, said base portion being provided with air-admitting openings, a back-wall unit adapted to be disposed on the base portion of the body unit, rearward of the opening therein to permit air circulation at the front face of the back-wall unit, in combination with radiant elements arranged along the front face of the back-wall unit, and a radiant rest disposed in the opening of the base portion of the body unit in insulated relation therewith.
10. A gas heater of the character described, composed of heat-resisting clay and comprising a body unit with upstanding ends and integral hollow base portion, having a burner-tip receiving opening in the upper face of the base portion, said base portion being formed with air-admitting openings and an expansion and contraction seam, and a back-wall unit adapted to have interlocking relation with the body unit and to permit air to circulate through said burner-tip receiving opening in the body unit.
11. A gas heater comprising a separate body unit and a separate back-wall unit, each composed of heat resisting clay and formed to have interlocking relation with each other to permit removal of the back-wall unit, the body unit having columnar ends between which the back-wall unit is placed, the body unit being formed with an open bottom and provided with a burner-tip receiving opening in the base intermediate of the columnar ends, in combination with a gas burner located in the open bottom of the body unit and unconnected therewith, the burner being provided with supporting standards whereby the burner is supported independently of the body unit.
12. A gas heater comprising a body unit and a back-wall unit having interlocking relation with each other to permit ready removal of the back-wall unit, the body unit being formed to receive a burner in the bottom thereof and provided with a burner-tip receiving opening, in combination with a gas-burner supported independent of the body unit, a radiant-rest arranged in said opening, and means whereby the position of said rest relative to the burner may be regulated.
